PRESTRESSED ALL-METAL ROOF
STRUCTURE

George M. Rapp, New Haven, Conn., assignor to
John B. Pierce Foundation, New York, N. Y.,
a corporation of New York

Application March 19, 1946, Serial No. 655,625

20 Claims. (Cl. 108—1)

1
The invention relates to pre-stressed arched roof structures.

An object of the invention is to provide a roof structure embodying the assembly of mutually correlated component sub-structures individually comprising a resilient slender member which is pre-stressed to bowed or arched configuration, the resulting roof structure being particularly adapted for building construction wherein low costs of material and of labor, lightness of weight and durability of assembly are paramount. Preferably, such pre-stressed resilient slender member is of metal, notably steel, thereby attaining enhanced structural strengths, and co-ordinating remaining elements of the roof structure also of metal, whereby resistance against fire is also attained.

In general, embodiments of the invention comprise a plurality of sets of individual substructures, each set of sub-structures spanning the opening to be covered by the roof structure, each such sub-structure comprising a slender member of resilient material, preferably of metal, pre-stressed to bowed formation, combined with co-ordinating parts for supporting such pre-stressed bowed member and maintaining the same in its said pre-stressed bowed status, the plurality of sets of such sub-structures respectively interconnected in seriatim overlapping relation with respect to one another completing the expanse of the roof. Usually each such set comprises two such sub-structures which when installed are conjoined, the pre-stressed members comprising component parts of a stable and load supporting structure, which may have general truss or triangular or general curvilinear or arch-like configuration, the abutting juxtaposed face portions of the conjoined pair of sub-structures at or adjacent the ridge line of the roof being secured to one another.

More specifically, pursuant to the most-preferred forms of the invention, the roof comprises a plurality of pairs of such sub-structures of substantially duplicate construction, the pre-stressed member of each sub-structure being in the form of a corrugated sheet member of metal, serving as the primary roof member, the corrugations of such corrugated member extending from the eave line to the ridge line of the roof, and one or more pairs of tension elements such as lengths of pipe, rods or wires, respectively, pivotally connected to the inner face of each such corrugated member. Each of these tension elements is provided with a turn-buckle, sleeve nut or the like for adjusting and pre-

5 stressing the corrugated member to its desired bowed configuration. Suitable ridge members are provided for spanning the joints at the abutting juxtaposed face portions of such pairs of such sub-structures at the ridge of the roof. The thrusts or outward forces caused by the truss or arch-like shape are carried by tension ties secured at their opposite ends at or adjacent to the eave lines. Suitable vertical strut members 10 support these tension ties at their mid-span points, which they connect to the ridge line of the roof. The roof thus is completed by duplicates of such pairs of sub-structures disposed in mutually seriatim overlapping relationship with one another.

15 The invention affords low cost of material in that ample factor of safety is attained by enhanced mechanical strengths imparted by the pre-stressed member, enabling relatively light materials to be utilized. Savings in labor costs are attained in that each such sub-structure may be assembled at a central location and shipped to the site of erection. Desirably, each such sub-structure is shipped "flat," that is to say, the corrugated or like member being in flat 20 status, the operation of pre-stressing such member being carried out at the site of erection by turning the turn-buckles or sleeve nuts to pre-stress the respective members to the desired uniform arch configuration.

25 Further features and objects of the invention will be more fully understood from the following detailed description and the accompanying drawings, in which:

30 **35** Fig. 1 is a perspective of a preferred form of roof construction embodying the invention, a pair of sub-structures being shown in substantial entirety, and indicated portions of adjacent seriatim overlapping sets of duplicate pairs of 35 sub-structures.

40 Fig. 2 is a detail sectional view on line 2—2 of Fig. 1.

45 Fig. 3 is a detail sectional view on line 3—3 of Fig. 1.

50 Fig. 4 is a detail view of the parts shown in Fig. 3, as appears from line 4—4 of Fig. 3.

Fig. 5 is a perspective view of the left hand sub-structure of the roof shown in Fig. 1, and its triangular support.

Fig. 6 is a top plan view of the sub-structure shown in Fig. 5, with the addition of a portion of the central ridge member.

Fig. 7 is a bottom plan view of Fig. 6.

Fig. 5, however, showing the sub-section in flat, i. e. non-stressed status.

Fig. 9 is a sectional view of Fig. 1, taken transversely of a pair of correlated sub-structures, supported in triangular relation with respect to the eave lines of opposite walls of the building.

Fig. 10 is a detail sectional view of a central portion of Fig. 9, on an enlarged scale.

Fig. 11 is a detail sectional view on line 11-11 of Fig. 9, on an enlarged scale.

Fig. 12 is a detail sectional view through the non-stressed roof element, showing a variant form of corrugation.

Fig. 13 is a detail section through the non-stressed roof element, showing another variant form of corrugation.

Referring to the preferred embodiment of the invention illustrated in Figs. 1, 5 and 9 of the drawings, the roof structure comprises a plurality of pairs of duplicate, conjoined sub-structures, the roof being completed by duplication of such pairs of conjoined sub-structures in seriatim overlapping relation, as is indicated in Figs. 1 and 7. 20 designates generally the pair of conjoined roof sub-structures shown in entirety in Fig. 1. 21, 21, indicates fragmentarily a pair of such duplicate conjoined sub-structures extending to the right of the pair 20, 20; 22, 22, similarly indicates fragmentarily a pair of such duplicate conjoined sub-structures extending to the left of the set 20, 20. Each pair of roof sub-structures abut one another at their juxtaposed faces, i. e., centrally of the roof, a ridge member serving to close the line of jointing thereat, such ridge members being arranged in seriatim overlapping relation, as appears more fully herein-after.

Each roof sub-structure comprises primarily a slender resilient member 23, preferably of sheet formation and of steel or the like, which is subjected to pre-stressing; preferably, also, such member 23 is corrugated, the apices of the corrugations extending from the eave line to the central ridge line. Desirably, such pre-stressing is effected, as shown, by means of a pair of stress rods 24, 24, one end of each rod being pivotally fulcrumed with respect to the inner face of the member 23, respectively adjacent the eave and ridge end portions of the member, tension being applied to such pair of rods 24, 24, as by a turn-buckle or sleeve nut 25, to thus pre-stress the corrugated member 23 under tension to its desired bowed configuration.

Specifically, the pivoted end of each of the pair of stress rods for each member 23 is pivotally fulcrumed in a clevis-like element. The clevis-like element at the eave line of each member 23 is designated 26; it is shown welded to a face 27a of one leg of the L-shaped plate 27, the face 27b of the other leg of the L-shaped plate being spot welded to the inner apices of the corrugations of the member 23, as shown in Figs. 1, 2, 5, 9, 10 and 11. The pivoted ends of the cooperating stress rods 24 adjacent the ridge line of each member 23, are fulcrumed in the clevis-like elements designated 28, a face of each of which, see Figs. 1, 5, 9 and 10, is welded to the inner face of the member 23 adjacent its ridge line. The two clevis-like elements 26, 28 of each member 23, are welded, as appears in Figs. 5 and 8, to a face 29a of one leg of the L-shaped plate 29, and the face 29b of such L-shaped plate is welded to the inner apices of the member 23.

Intermediate the eave line and the ridge line of each member 23, and on the inner face there-

of are plates 30, 30, shown of flattened U-shape, which are spot welded to the inward apices of the corrugations of each member. Each plate 30 is provided with transverse closed-ended slots 30a, 30a, through which pass the respective stress rods 24, 24, 24, 24.

Upon joining the pair of correlated sub-structures spanning a given portion of the roof, the abutting juxtaposed faces of the L-shaped plates 29, 29, are rigidly connected to one another, as by bolting, which may be performed on location.

Desirably, the joint at the ridge line of the roof and the adjacent ridge portions of each pair of conjoined sub-structures are sheathed by a ridge member, preferably an arcuated ridge member 21, as shown in Figs. 1, 5, 9 and 10, such ridge member being rigidly secured to the underlying ridge portions of such pair of sub-structures, preferably by self-tapping screws, indicated at 32, 32, in Fig. 10.

Each pair of sub-structures, as shown in the illustrated preferred embodiment, is supported in triangular spanned relation relative to the walls of the building or other construction, as by the assembly of horizontal beams in turn carrying at their centers vertically extending plates in turn supporting the ridge portions of the sub-structures. As illustrated in Figs. 1, 5 and 9, and fragmentarily in Fig. 10, such triangularly configurated assembly includes the horizontal extending beams 33, shown of U-shape. The opposite eave ends 33a of each of such beams are shown secured to plates 34, 34, as by means of bolts or equivalent indicated at 35, such plates 34, 34, being secured to the upper faces of the building walls indicated at 35, 35. As shown, such plates 34, 34, are each secured to the underfaces of the respective clevis-like elements 26, 26, as by welding, and in turn secured by bolts 36, 36, to the respective walls 37, 37, of the building. Desirably, as shown in Fig. 2, a buttress of wood or steel indicated at 38 secured to the top of each wall 35, is interposed, with which buttress the associated clevis-like element 26 is secured, as by the bolts 36. Such buttress 38 serves as a cushion of limited yield, advantageous in the circumstance when the roof structure is subjected to substantial stresses, as under high wind conditions.

It will be observed from Figs. 1, 2 and 9, that the free ends of the eave disposed L-shaped plates 27 of the seriatim pairs of conjoined sub-structures butt one another. The joints thus formed may be protected so as to accomplish a weather-seal by bolted or screw-attached splice plates.

Associated with such horizontal extending beam 33 are the vertically extending supporting plates 39, see Figs. 1, 5, 9 and 10, shown carried at their lower ends by the beams 33. Such plates 39, as indicated, may be of U-shape, and secured at the lower ends of the respective beams 33 by bolts, as indicated at 40 in Fig. 9. To the upper end of each supporting plate 39, as shown in Figs. 9 and 10, is secured a bracket 41.

As indicated in Figs. 1, 5 and 9, the extent of pre-stressing of each roof member 23 is determined by the total span of the roof, the individual roof members 23 being bowed to substantially uniform arch configuration. In general, such arch is of low arcuate configuration, the plurality of sets of conjoined sub-structures forming a resulting roof of low pitch.

When shipped from the factory, or other location of pre-assembly, and/or when placed in

storage, each sub-structure is desirably in flat status, as is illustrated in Fig. 8, that is to say, the turn-buckle 28, or equivalent being in slack relation with the stress rods 24, 24, the roof element 23 being thus in flat status.

Upon bowing the respective roof members 23 to the desired pre-stressed status, as indicated in Figs. 3 and 4, a yoke bolt 42 may be employed to interconnect each rod length 24 with the lower flange of the U-shaped plate 30, and tightened by nuts 43. Desirably, shims, indicated at 44 in Fig. 3, are interposed between the flange of the plate 30 and the free ends of the yoke bolt, and tightened by nuts 44.

From the above it is apparent that the resulting roof structure may be constituted of relatively light weight parts, and nevertheless by reason of the high mechanical strength imparted by the pre-stressed roof members 23 and their respective pairs 24, 24, of stress rods in tension, the roof structure possesses a high factor of safety.

The roof structure attained by the embodiment illustrated in Figs. 1 through 11 is of particular application for farm service structures, such as barns, sheds, poultry and hog houses, corn cribs, etc., for which purpose the pre-stressed corrugated sheet members 23 serve as the primary roof elements.

In Figs. 1 through 11 the members 23 are indicated of uniform arcuate corrugations; however, other forms of corrugation for the members 23 may be employed. Figs. 12 and 13 illustrate variant types of corrugation applicable to the invention. In Fig. 12 the resilient sheet member has rectangular trough-like corrugations, whereas the resilient sheet member, shown in Fig. 13 the corrugations are of frusto-tapering formation.

Non-corrugated sheets of resilient metal such as steel or of other suitable material may also be employed for the members 23, as will be apparent. In such application of the invention the outer surfaces of the non-corrugated members may be covered by conventional sheet roofing material, secured by asphaltic or like water-repelling and weather-resisting cement.

I claim:

1. A roof sub-structure comprising in combination a member of resilient sheet material; correlated slender elements fulcrumed at their respective one ends to an inner face of said sheet member; and means respectively connected to the respective opposite ends of said slender elements for drawing the stated points of fulcrum of said slender elements to thereby subject said sheet member to tension and thereby causing said sheet member to assume a bowed configuration.

2. A roof sub-structure comprising in combination a member of resilient corrugated sheet material; correlated slender elements fulcrumed at their respective one ends to an inner face of said sheet member; and means respectively connected to the respective opposite ends of said slender elements for drawing the stated points of fulcrum of said slender elements to thereby subject said sheet member to tension and thereby causing said sheet member to assume a bowed configuration.

3. A roof sub-structure comprising in combination a member of resilient sheet material, said sheet member being corrugated and having its peaks of corrugations extending from the eave line upwardly of the roof; correlated slender elements fulcrumed at their respective one ends to

an inner face of said sheet member; and means respectively connected to the respective opposite ends of said slender elements for drawing the stated points of fulcrum of said slender elements to thereby subject said sheet member to tension and thereby causing said sheet member to assume a bowed configuration.

4. A roof sub-structure comprising in combination a member of resilient corrugated metallic sheet material; correlated slender elements fulcrumed at their respective one ends to an inner face of said sheet member; and means respectively connected to the respective opposite ends of said slender elements for drawing the stated points of fulcrum of said slender elements to thereby subject said sheet member to tension and thereby causing said sheet member to assume a bowed configuration.

5. A roof sub-structure comprising in combination a member of resilient metallic sheet material, said sheet member being corrugated and having its peaks of corrugations extending from the eave line upwardly of the roof; correlated slender elements fulcrumed at their respective one ends to an inner face of said sheet member; and means respectively connected to the respective opposite ends of said slender elements for drawing the stated points of fulcrum of said slender elements to thereby subject said sheet member to tension and thereby causing said sheet member to assume a bowed configuration.

6. A roof sub-structure comprising in combination a member of resilient sheet material; correlated slender elements fulcrumed at their respective one ends to an inner face of said sheet member; and means respectively connected to the respective opposite ends of said slender elements for drawing the stated points of fulcrum of said slender elements to thereby subject said sheet member to tension and thereby causing said sheet member to assume a bowed configuration.

7. A roof sub-structure comprising in combination a member of resilient sheet material; correlated slender elements fulcrumed at their respective one ends to an inner face of said sheet member; and means respectively connected to the respective opposite ends of said slender elements for drawing the stated points of fulcrum of said slender elements to thereby subject said sheet member to tension and thereby causing said sheet member to assume a bowed configuration; and means of general triangular configuration for supporting said roof sub-structure.

8. A roof sub-structure comprising in combination a member of resilient corrugated sheet material; correlated slender elements fulcrumed at their respective one ends to an inner face of said sheet member; and means respectively connected to the respective opposite ends of said slender elements for drawing the stated points of fulcrum of said slender elements to thereby subject said sheet member to tension and thereby causing said sheet member to assume a bowed configuration; and means of general triangular configuration for supporting said roof sub-structure.

9. A roof sub-structure comprising in combination a member of resilient corrugated metallic sheet material; correlated slender elements fulcrumed at their respective one ends to an inner face of said sheet member; and means respectively

connected to the respective opposite ends of said slender elements for drawing the stated points of fulcrum of said slender elements to thereby subject said sheet member to tension and thereby causing said sheet member to assume a bowed configuration; and means of general triangular configuration for supporting said roof sub-structure.

10. A roof sub-structure comprising in combination a member of resilient metallic sheet material, said sheet member being corrugated and having its peaks of corrugations extending from the eave line upwardly of the roof; correlated slender elements fulcrumed at their respective one ends to an inner face of said sheet member; means respectively connected to the respective opposite ends of said slender elements for drawing the stated points of fulcrum of said slender elements to thereby subject said sheet member to tension and thereby causing said sheet member to assume a bowed configuration; and means of general triangular configuration for supporting said roof substructure.

11. A roof structure formed of a plurality of sets of conjoined roof sub-structures, each roof sub-structure comprising in combination a member of resilient sheet material; correlated slender elements fulcrumed at their respective one ends to an inner face of said sheet member; means respectively connected to the respective opposite ends of said slender elements for drawing the stated points of fulcrum of said slender elements to thereby subject said sheet member to tension and thereby causing said sheet member to assume a bowed configuration; means of general triangular configuration for supporting said roof sub-structures; and ridge enclosing means secured to the resulting roof structure adjacent and extending over the juxtaposed portions of the respective sets of conjoined roof sub-structures.

12. A roof structure formed of a plurality of sets of conjoined roof sub-structures, each roof sub-structure comprising in combination a member of resilient corrugated sheet material; correlated slender elements fulcrumed at their respective one ends to an inner face of said sheet member; means respectively connected to the respective opposite ends of said slender elements for drawing the stated points of fulcrum of said slender elements to thereby subject said sheet member to tension and thereby causing said sheet member to assume a bowed configuration; means of general triangular configuration for supporting said roof sub-structures; and ridge enclosing means secured to the resulting roof structure adjacent and extending over the juxtaposed portions of the respective sets of conjoined roof sub-structures.

13. A roof structure formed of a plurality of sets of conjoined roof sub-structures, each roof sub-structure comprising in combination a member of resilient sheet material, said sheet member being corrugated and having its peaks of corrugations extending from the eave line upwardly of the roof; correlated slender elements fulcrumed at their respective one ends to an inner face of said sheet member; means respectively connected to the respective opposite ends of said slender elements for drawing the stated points of fulcrum of said slender elements to thereby subject said sheet member to tension and thereby causing said sheet member to assume a bowed configuration; means of general triangular configuration for supporting said roof sub-structures; and ridge enclosing means se-

cured to the resulting roof structure adjacent and extending over the juxtaposed portions of the respective sets of conjoined roof sub-structures.

- 5 14. A roof structure formed of a plurality of
sets of conjoined roof sub-structures, each roof
sub-structure comprising in combination a mem-
ber of resilient corrugated metallic sheet ma-
terial; correlated slender elements fulcrumed
10 at their respective one ends to an inner face of
said sheet member; means respectively connected
to the respective opposite ends of said slender
elements for drawing the stated points of fulcrum
15 of said elongated elements to thereby subject said
sheet member to tension and thereby causing
said sheet member to assume a bowed configura-
tion; means of general triangular configuration
20 for supporting said roof sub-structures; and
ridge enclosing means secured to the resulting
roof structure adjacent and extending over the
juxtaposed portions of the respective sets of con-
joined roof sub-structures.

15 15. A roof structure formed of a plurality of
sets of conjoined roof sub-structures, each roof
sub-structure comprising in combination a mem-
ber of resilient metallic sheet material, said sheet
25 member being corrugated and having its peaks of
corrugations extending from the eave line up-
wardly of the roof; correlated slender elements
30 fulcrumed at their respective one ends to an in-
ner face of said sheet member; means respec-
tively connected to the respective opposite ends of
35 said slender elements for drawing the stated
points of fulcrum of said slender elements to
thereby subject said sheet member to tension and
thereby causing said sheet member to assume a
40 bowed configuration; means of general triangu-
lar configuration for supporting said roof sub-
structures; and ridge enclosing means secured to
the resulting roof structure adjacent and extend-
45 ing over the juxtaposed portions of the respective
sets of conjoined roof sub-structures.

45 16. A roof structure formed of a plurality of
sets of conjoined roof sub-structures, each roof
sub-structure comprising in combination a mem-
ber of resilient slender material; correlated slender
50 elements fulcrumed at their respective one ends
to an inner face of said slender member; means respec-
tively connected to the respective
55 opposite ends of said slender elements for draw-
ing the stated points of fulcrum of said slender
elements to thereby subject said slender member
to tension and thereby causing said slender
member to assume a bowed configuration; and
means of general triangular configuration for
supporting said roof sub-structures.

55 17. A roof structure formed of a plurality of
sets of conjoined roof sub-structures, each roof
sub-structure comprising in combination a mem-
ber of resilient corrugated slender material; cor-
60 related slender elements fulcrumed at their re-
spective one ends to an inner face of said slender
member; means respectively connected to the re-
spective opposite ends of said slender elements
65 for drawing the stated points of fulcrum of said
slender elements to thereby subject said slender
member to tension and thereby causing said
slender member to assume a bowed configura-
70 tion; and means of general triangular configu-
ration for supporting said roof sub-structures.

70 18. A roof structure formed of a plurality of
sets of conjoined roof sub-structures, each roof
sub-structure comprising in combination a mem-
ber of resilient slender material, said slender
75 member being corrugated and having its peaks

of corrugations extending from the eave line upwardly of the roof; correlated slender elements fulcrumed at their respective one ends to an inner face of said slender member; means respectively connected to the respective opposite ends of said slender elements for drawing the stated points of fulcrum of said slender elements to thereby subject said slender member to tension and thereby causing said slender member to assume a bowed configuration; and means of general triangular configuration for supporting said roof sub-structures.

19. A roof structure formed of a plurality of sets of conjoined roof sub-structures, each roof sub-structure comprising in combination a member of resilient corrugated metallic slender material; correlated slender elements fulcrumed at their respective one ends to an inner face of said slender member; means respectively connected to the respective opposite ends of said slender elements for drawing the stated points of fulcrum of said slender elements to thereby subject said slender member to tension and thereby

causing said slender member to assume a bowed configuration; and means of general triangular configuration for supporting said roof sub-structures.

5 20. A roof structure formed of a plurality of sets of conjoined roof sub-structures, each roof sub-structure comprising in combination a member of resilient metallic slender material, said slender member being corrugated and having its 15 peaks of corrugations extending from the eave line upwardly of the roof; correlated slender elements fulcrumed at their respective one ends to an inner face of said slender member; means respectively connected to the respective opposite ends of said slender elements for drawing the stated points of fulcrum of said slender elements to thereby subject said slender member to tension and thereby causing said slender member to assume a bowed configuration; and means of 20 general triangular configuration for supporting said roof sub-structures.

GEORGE M. RAPP.
